CARBON-SHEET SUPPORT FOR
TYPEWRITERS

Claude Wellington Brumhill, Leicester, England,
assignor to Imperial Typewriter Co. Ltd.,
Leicester, England

Application January 30, 1942, Serial No. 428,965
In Great Britain February 26, 1941

8 Claims. (Cl. 282—3)

This invention is for improvements in and relating to carbon sheet supports for typewriters, and is concerned with a carbon support of the type adapted for use in the production of a plurality of carbon copies wherein carbon sheets are interleaved with paper sheets to travel therewith towards the platen, comprising a trolley or other support member movable towards and away from the platen, and carbon blade mounting means for removably receiving at different levels a plurality of fingers or blades which extend across the path of movement of the trolley and have the rear edges of the carbon sheets secured to them. Carbon supports of this type are commonly employed in continuous stationary typewriting machines; i. e., machines drawing their paper as a continuous multi-ply web from a bulk supply thereof (often a zig-zag pile). The web of paper is passed over the trolley or the like, and the blades, each with its attached carbon sheet, are inserted between the plies of paper and are attached to the carbon support so that the carbons extend from the blades (between the plies of paper) towards the platen. The interleaved paper and carbon is then taken around the platen, so that as typing proceeds the carbons and the carriage are drawn towards the platen with the paper. Subsequently, when it is desired to tear off the typed length from the web or when the blades have been drawn up to the carriage, the feeding grip on the web is relaxed and the trolley or the like is moved back carrying the carbon sheets with it.

The present invention provides in or for a typewriter, a carbon support of the type specified having carbon blade mounting means arranged for the reception of the blades in substantial register each with the next and permitting of the mounting or removal of the blades one by one. Thus in operation all the blades are located at substantially the same distance from the platen and the forward edges of the carbon sheets are substantially level with one another. This is of considerable advantage, as is also the ability to mount or remove the blades one by one.

According to an important subsidiary feature of the invention, the carbon support has a blade-receiving-socket, superimposed blade slots across it for the reception of the blades in a tier, and locking means for locking the blades in their slots. Advantageously, the socket is pierced with at least one hole in the slotted portion thereof, and for each said hole there is a plunger arranged to transfix the blades when the latter are received in said slots.

The foregoing and other features of the invention set out in the appended claims are incorporated in the preferred construction now to be described in detail with reference to the accompanying drawing, in which

Figure 1 is a fragmentary front elevational view of a carbon carrier constructed in accordance with the invention; and

Fig. 2 is a plan view of the parts shown in Fig. 1.

The carbon carrier comprises a pressed steel trolley 10 which is mounted for movement towards and away from the carriage of the machine upon track strips 11, themselves secured to longitudinal members of a framework 12. It will be observed from Fig. 1 that the strip 11 there shown is engaged between two grooved rollers 13 mounted at the underside of the trolley 10.

20 The frame 12 is adapted to be attached at its forward end, by means indicated at 23, to the carriage of the machine so that it partakes of the carriage-traversing movement.

25 Detachably secured to the trolley 10 by means hereinafter described there is a pressed steel platform 15 on which the carbon paper fingers or blades 16 are mounted each in substantial register with the next above and/or below it. Near each end the said platform 15 is provided with 30 a bifurcated metal block indicated generally by the numeral 17. This metal block has a substantially vertical cleft 18 extending in the direction of movement of the trolley 10 whereby said block is divided into two upstanding pillars 17'. At the 35 forward face of each block, i. e., that face which is directed towards the platen, the pillars 17' are cut across with a suitable number of horizontal slots 19, one above the other. These slots are for the reception of the outer ends of the blades 16,

40 and the slots in the left hand block are at different levels from those in the right-hand block whereby the blades 16 projecting inwards from the two blocks are interleaved or intercalate. The pillars 17' of each block are each pierced 45 with a vertical hole 20 and the outer ends of the blades 16 are provided with similar holes which, when the blades are placed in the slots 19, register with said holes 20. This permits staple-like or inverted U-shaped keys 21 to be 50 dropped into the holes 19 thereby transfixing the blades 16 and securing them in position. It may here be mentioned that in order to facilitate the entry of the blades into the slots 19 with their holes in register with the holes 20, each blade 55 has a button 22 riveted to it to engage in the

cleft 18 in the appropriate block. Reference to Fig. 2 shows that the blades 16 do not extend absolutely normal to the line of movement of the trolley 10 but are slightly inclined to the normal in a rearward direction, a suitable angle being $1\frac{1}{2}^{\circ}$. The object of this slight inclination is to throw the side edges of the carbons adjacent to the typing station into the folds of the paper when folded paper is employed, it being appreciated that the free ends of the blades 16 will be adjacent to the folds.

The keys 21 are completely removable from the blocks 19, but normally are not so removed. They are releasably retained in position by means of spring pressed plungers 24 in the pillars 17, which plungers, when the keys are pressed home, engage recesses cut in the keys at a suitable upper level and which, when the keys are pulled upwards to clear the uppermost blades, engage other recesses cut in the keys at a suitable lower level.

It will be appreciated that the above described mounting for the blades 16 permits any of them to be inserted or withdrawn without disturbing the others. For example if it is desired to remove or insert the lowermost blade this is readily effected by raising the appropriate key 21 to the required height to disengage from the holes in said blade whereupon the blade may be removed from its lock 17. If it is desired to remove or insert the uppermost blade the appropriate key is withdrawn to its full height whereupon the blade may be inserted into or removed from its block 17 without disturbing the blades below it which remain in position.

The platform 15 which is provided with a handle, part of which is shown at 25, whereby it may be moved fore-and-aft on the frame 12.

The forward advance of the trolley 10 and platform 15 is cushioned by leaf springs 30 attached to the connecting means 23 aforesaid, and rearward movement is cushioned by a leaf spring 31 which is attached to the rear edge of the trolley 10 to strike against an adjustable stop mounted on one of the track strips 11. Furthermore, in order to absorb shock when tabulating the traversing movements of the carriage 12 are cushioned by buffer springs 35 associated with the carriage attachment means 23 aforesaid, the operation of which buffer springs will be apparent from Figure 2.

Adjustable web guides are provided on the platform 15 for determining the location of the web of paper in the width of the carbon carrier. Each paper guide comprises a spindle 36 which is attached to a plate 37 underneath the platform 15 and extends upwards through a transverse slot 38 therein. Above the platform 15 spindle 36 is surrounded by a sleeve 39 and at its upper end is provided with a knurled nut 40. It will therefore be appreciated that by unscrewing the nut the guide may be moved transversely, and by screwing the nut up the guide may be clamped in the desired position of adjustment. Alternatively, the part indicated at 40 may be a head integral with the spindle 36 and the part 37 may be a plate nut into which the spindle screws. Preferably at the base of the sleeve 39 a guard plate 41 is provided to slide over the upper surface of the platform 15.

In setting up the carrier for use with stationery drawn from a continuous supply thereof and folded at intermediate points in its width into several plies so as to afford a top copy and the required number of carbon copies, the mul-

ti-ply web is drawn over the surface of the platform 15 with the latter in its rearward position and the blades 16 removed. Sheets of carbon are then attached one to each blade either by 5 passing each blade through a hem provided at the rear edge of the carbon sheet, or by securing the rear edge of the carbon sheet to the blade by means of clips. The blades with the attached carbon sheets are then inserted one 10 by one, commencing with the lowermost, between the successive plies of paper, the free end of each blade being adjacent to a fold in the paper. Thus considering the folds at, for example, the left-hand edge of the web, the 15 blades 16 are inserted from the right-hand edge of the paper supply. As each blade is inserted between the plies of paper it is inserted into a slot 19 in the appropriate block 17 and its button 20 is received in the cleft 18. When all the 20 blades have been thus inserted the keys 21 are pressed down and the interleaved paper and carbons may then be taken around the platen in the normal manner. As typing proceeds the paper is drawn off from the supply by the rotation of the platen and simultaneously the trolley 25 10 and platform 15 are drawn forward on the frame 12. Subsequently when a sufficient length of typing has been produced (as for example in making out an invoice) or when the trolley 10 has reached the forward extremity of its advance, the platen is raised to relax the feeding grip on the paper and carbons and the trolley is pushed backwards by means of the handle 25, the carbons sliding back between the 30 plies of paper.

Although in the illustrated construction two oppositely-directed sets of blades 16 are shown, it is within the scope of the invention to provide a single block 17 or other socket, at one 40 edge of the web, for the reception of one set of blades.

I claim:

1. In a carbon support for a manifolding typewriter, for use in the production of a plurality of carbon copies through the medium of carbon sheets interleaved with paper sheets to travel towards the typewriter platen: carbon blade mounting means comprising a socket member having superimposed blade slots across it for the reception of the blades in a tier; and locking means for locking the blades in said slots and for permitting their mounting therein or removal therefrom one by one.

2. A carbon support for a manifolding typewriter, for use in the production of a plurality of carbon copies through the medium of carbon sheets interleaved with paper sheets to travel towards the typewriter platen, said support having a blade-receiving socket member provided with means for the reception of carbon blades in a tier with each blade in substantial registry with the next; and locking means for locking the blades to the socket member and for releasing any selected blade for removal from the socket without the removal of the remainder of the blades.

3. A carbon support of the type specified for a manifolding typewriter, comprising a blade-receiving socket provided with superimposed blade slots across it for the reception of the blades in a tier and with at least one hole in the slotted portion thereof for the reception of a plunger and a plunger arranged to enter said hole to transfix the blades when the latter are received in the slots.

4. A carbon support according to claim 3, hav-

ing a cleft in the socket, dividing the latter into two portions spaced lengthwise of the blades and each having a plunger hole, and blades each having a projection thereon for engagement in the cleft.

5. A carbon sheet support of the type specified, for manifolding typewriters, having two carbon blade sockets, spaced apart to permit the web of paper to pass between them, superimposed blade slots in each socket for the reception of blades in a tier, the slots in one socket being at levels mid-way between the slots in the other socket, and locking means for locking the blades in their slots.

6. A carbon sheet support of the type specified for manifolding typewriters, having two carbon blade sockets, placed apart to permit the web of paper to pass between them, superimposed blade slots in each socket for the recep-

tion of blades in a tier, the slots in one socket being at levels mid-way between the slots in the other socket, and locking means for locking blades in their slots and permitting of their mounting or removal one by one.

7. A carbon support of the type specified for a manifolding typewriter, comprising a blade-receiving socket provided with superimposed blade slots across it for the reception of the blades in a tier and with two holes in the slotted portion thereof for the reception of plungers for transfixing the blades when received in the slots, and two plungers mounted in said holes for movement between a fully inserted position and a position in which they clear all of the slots.

8. A carbon support according to claim 7, having means for retaining each plunger in each of its two said positions.
